UNITED STATES PATENT OFFICE.

LOUIS MERZ, OF NEW YORK, N. Y., ASSIGNEE TO THE JOHN J. LATTEMAN SHOE MFG. CO., OF BROOKLYN, NEW YORK.

DESIGN FOR A SLIPPER.

40,391.

Specification for Design.

Patented Dec. 7, 1909.

Application filed March 30, 1909. Serial No. 486,827. Term of patent 8 years.

To all whom it may concern:

Be it known that I, Louis Merz, a subject of the Emperor of Germany, and a resident of the borough of Brooklyn, in the city of New York and State of New York, have invented a new and original Design for Slippers, of which the following is a specification, reference being had to the accompanying drawing, forming a part hereof.

The figure is a perspective view illustrating a slipper embodying my invention.

As shown in the drawing the leading or material features of the new design consists in the production of an artistic configuration and ornamentation of a slipper consist-

ing of a series of diamonds placed one above the other and bound by artistic stripes, artistic buttons being located at the acute corners of the diamonds along one side, the said diamonds being interspersed by lobes having acute angles complementing the obtuse angles of the diamonds.

I claim—

The ornamental design for a slipper as shown and described.

LOUIS MERZ.
